DESIGN FOR A LIGHTING FIXTURE

Oscar Richter, New Rochelle, N. Y., assignor to Richter Metalcraft Corp., Mount Vernon,
N. Y.

Application May 11, 1946, Serial No. 129,593

Term of patent 3½ years

(Cl. D48—23)

To all whom it may concern:

Be it known that I, Oscar Richter, a citizen of the United States, residing at New Rochelle, in the county of Westchester and State of New York, have invented a new, original, and ornamental Design for a Lighting Fixture, of which the following is a specification, reference being had to the accompanying drawing, forming part thereof.

Fig. 1 is a top view of an ornamental lighting fixture, showing my new design;

Fig. 2 is a side elevation thereof;

Fig. 3 is an end elevation thereof;

Fig. 4 is a fragmental section taken along line 4—4 of Fig. 3; and

Fig. 5 is a section taken on line 5—5 of Fig. 4.

I claim:

The ornamental design for a lighting fixture, as shown.

OSCAR RICHTER.
